Primary Examiner — Cynthia Underwood*(74) Attorney, Agent, or Firm* — The Roy Gross Law Firm, LLC; Roy Gross(57) **CLAIM**

The ornamental design for an adjustable frame, as shown and described.

DESCRIPTION

FIG. 1 is a front isometric view of an adjustable frame in accordance with the new design;

FIG. 2 is a front view thereof;

FIG. 3 is a right side elevation view thereof;

FIG. 4 is a rear view thereof;

FIG. 5 is a left side elevation view thereof;

FIG. 6 is a bottom elevation view thereof;

FIG. 7 is a top elevation view thereof; and,

FIG. 8 is a front exploded isometric view thereof.

The broken lines that are part of the structure form no part of the claim. The broken line rectangles that are off to the far side of the claim represent environment and form no part of the claim.

1 Claim, 8 Drawing Sheets(56)
